UNITED STATES PATENT OFFICE.

WILLIAM H. DENNIS, OF EXETER, NEW HAMPSHIRE.

RAIL-BRACE.

1,267,990.

Specification of Letters Patent. Patented May 28, 1918.

Application filed April 3, 1917. Serial No. 159,516.

To all whom it may concern:

Be it known that I, WILLIAM H. DENNIS, a citizen of the United States, residing at Exeter, in the county of Rockingham and State of New Hampshire, have invented certain useful Improvements in Rail-Bracers, of which the following is a specification, reference being had therein to the accompanying drawing.

10 The present invention relates to a brace adapted for engagement with a rail, to hold the same from spreading or tilting when subjected to lateral strain on curves and the like.

15 It is an object of this invention to provide a brace of this nature which may be easily attached to rails which are already laid, which will protect the tie from wearing at one side of the base of the rail, as is common in present use; and to provide a brace which may be positioned without the use of the ordinary spikes, and wherein the fastening means employed is not subjected to the heavy strain to which the usual railroad spikes are submitted.

The invention further aims at the provision of a brace of this character which may be economically manufactured, produced and handled.

20 Other objects and advantages of this invention, as well as the above, will be brought out more specifically in the following detailed description of the present preferred embodiment of this invention, the same being illustrated in the accompanying drawing, wherein—

Figure 1 is a transverse sectional view of a track having the improved brace applied to one rail thereof.

25 Fig. 2 is a top plan view of the outer rail of a curve having the improved brace applied thereto.

Fig. 3 is a detail perspective view of the body portion of the brace.

30 Fig. 4 is a detail perspective view of the interlocking part of the brace.

Referring to this drawing, 10 and 11 designate the rails of a track, the outer rail 10 having the brace of this invention applied thereto. The rails are supported in the usual manner upon ties 12.

The brace comprises a body member 13, which is preferably stamped from sheet steel, and being substantially of U-shape.

35 The opposite arms of the body member 13

are bent downwardly from the ends of the web or intermediate portion of the body and have at their outer ends under-cut upstanding projections providing hooks 14 adapted for engagement over the base of 60 the rail 10. The arms, designated at 15, are adapted to lie against the opposite sides of one of the ties 12. The web of the body portion is of a length to extend across the upper face of a tie and to hold the arms 15 65 against the opposite sides thereof. The arms 15 project beneath the rail and support the hooks 14 in such position as to engage the base flange of the rail at the inner side of the latter, and thus hold the rail 70 from tilting outwardly. A single fastening device, such as an ordinary spike 16, is secured downwardly through the web of the member 13 and into the tie for the purpose of holding the body member from sliding 75 longitudinally on the tie 12.

An inter-locking member 17, which is also preferably stamped from sheet steel, is provided with a main web portion of a width adapted to fit snugly between the inner edge 18 of the body 13, and the adjacent edge of the base of the rail. The inter-locking member is secured by a single spike 19 to the top of the tie 12, the spike merely holding the web portion from lifting upwardly from within the body member.

80 The web of the member 17 has at its opposite ends upturned lugs 20, which extend inwardly toward, and are adapted to engage against the web of the rail 10, the lugs 20 90 engaging beneath the rail head to support the outer side thereof.

By the use of this improved brace, the rail 10 is held from tilting outwardly when subjected to abnormal strain, and the ties 95 12 are protected from the biting or wearing of the base flange of the rail across the upper faces of the ties.

It is of course understood that various changes and modifications may be made in 100 this structure, without departing from the spirit of this invention, such changes and modifications being limited only by the scope of the following claim.

105 What is claimed is:—

A rail brace including a U-shaped body member stamped from a single piece of sheet metal and embodying a web and sides adapted to be straddled about a tie, means for securing the web of the body member, 110

arms projecting inwardly from the sides of the body member and adapted to lie upon opposite sides of the tie, upwardly and inwardly projecting hooks on the free ends 5 of the arms adapted to engage the upper surface of one side of the base of a rail, an interlocking member also stamped from a blank of sheet metal and embodying a web adapted to be snugly arranged between the 10 web of a body member and the opposite side

of the rail base and on the upper surface of the tie, upwardly and inwardly extending lugs on the opposite sides of the web of the interlocking member and adapted to engage the opposite side of the rail web and 15 beneath the head of the rail, and means for securing the interlocking member.

In testimony whereof I affix my signature.

WILLIAM H. DENNIS.
